PICTURE FRAME

Richard L. Shinnick, 10659 Cranks Road,
Culver City, Calif. 90230

Filed Apr. 6, 1972, Ser. No. 241,879

Term of patent 14 years

Int. Cl. D6—07

U.S. Cl. D6—234

FIG. 1

FIG. 2

FIG. 3

FIG. 4

FIG. 1 is a front elevational view of a picture frame showing my new design;

FIG. 2 is a side elevational view thereof;

FIG. 3 is a rear elevational view thereof;

FIG. 4 is a bottom plan view thereof.

The essential feature of my design resides in the particular aperture arrangement on the front panel.

I claim:

The ornamental design for a picture frame, substantially as shown and described.
